United States Patent

Des. 240,480
Patented July 13, 1976

240,480

CHAIR

Robert J. Marks, 210 Johnson Ferry Road,
Atlanta, Ga. 30328

Filed Mar. 4, 1975, Ser. No. 555,169

Term of patent 14 years

Int. Cl. D6—01

U.S. Cl. D6—37

FIG. 1 is a perspective view of a chair embodying my new design;

FIG. 2 is a front elevational view of the chair shown in FIG. 1;

FIG. 3 is a side elevational view of the chair shown in FIG. 1;

FIG. 4 is a rear elevational view of the chair shown in FIG. 1; and,

FIG. 5 is a bottom view of the chair shown in FIG. 1. That side of the chair not shown is a mirror image of that side shown.

The surface material schematically shown on the several views is continuous throughout.

I claim:

The ornamental design for a chair, substantially as shown and described.
